UNITED STATES PATENT OFFICE

2,210,525

BASE FOR INCANDESCENT LAMPS AND
SIMILAR DEVICESCarl A. Brown, Chardon, and Clarence E. Hahn,
Cleveland, Ohio, assignors to General Electric
Company, a corporation of New York

Application May 14, 1938, Serial No. 207,964

6 Claims. (Cl. 176—32)

Our invention relates to electric incandescent lamps and similar devices comprising a bulb having an electrical energy translation element sealed therein and a base mounted on said bulb. More particularly, our invention relates to bases for such devices which usually consist of a metallic shell and a bottom end contact separated from each other by a suitable insulating medium.

In the present commercial form of lamp base, 10 the bottom end or center contact consists of a small brass eyelet mounted on the base insulation, to which eyelet one of the filament lead wires is soldered. Although this form of end contact has proven satisfactory, still the elimination 15 of the use of the brass eyelet is a highly desirable feature in view of the resulting saving in brass and reduction in the cost of base manufacture. While the elimination of the brass eyelet has been heretofore proposed by the use of simply a quantity 20 of solder or other suitable conductive material as the end contact, the results therefrom have not been entirely satisfactory for the reason that the solder does not completely fill the recess provided therefor in the base insulation. As a 25 result, the pressure exerted on the solder by repeated insertion of the lamp into its socket forces the solder to flow into the unfilled portions 30 of the recess, thereby lessening the initial assembled height of the solder above the base shell and base insulation to the point where engagement of the solder end contact with its corresponding socket contact is oftentimes entirely prevented.

One object of our invention is to provide an 35 electric incandescent lamp or similar device in which the customary base end contact eyelet is eliminated and a quantity of conductive fusible material employed as the end contact.

Another object of our invention is to provide 40 an electric incandescent lamp or similar device with a bottom end contact consisting solely of a globule of conductive and readily fusible material which will maintain its originally assembled height above the base shell and base insulation.

Still another object of our invention is to provide 45 a lamp base with a recess in the insulation thereof of such shape as to substantially conform to the contour of a drop of solder or other fusible material, whereby the said material completely fills the recess.

Further objects and advantages of our invention will appear from the following description of a species thereof and from the accompanying drawing in which:

Fig. 1 is a side view, partly in section, of an electric incandescent lamp provided with a base end contact comprising our invention; Fig. 2 is an enlarged fragmentary sectional view of the base end of the lamp shown in Fig. 1; Fig. 3 is a plan view of a preformed insulator button for a lamp base provided with a recess shaped according to our invention; and Fig. 4 is a sectional view taken on the line 4—4 of Fig. 3.

Referring to the drawing, there is shown in 10 Fig. 1 an electric incandescent lamp comprising a bulb 10 having a filament (not shown) sealed therein and a base 11 attached to the neck 12 of the bulb by suitable cement 13. The base 11 consists of a threaded metallic shell 14, preferably of brass, together with suitable insulation 15, preferably of glass, and a bottom end contact 16. One end of the lamp filament is connected to the base shell 14 by means of a lead 17 bent back over the end of the bulb neck and soldered at 18 to the edge of the said shell. The other end of the lamp filament is connected to a lead 19 which extends through a centrally located opening 20 in the glass insulation 15 into a recess 21 in the upper surface of the glass insulation where the said lead is secured by means of a drop of solder 22 or other similar fusible material to thereby form the lamp end contact. The glass insulation 15 is preferably made as a preformed button and is provided with a plurality of projections 23 (Figs. 2 and 3) on its upper surface and adjacent its periphery, as described and claimed in our co-pending application Serial No. 207,965, of even date herewith. These projections are formed with arcuate side walls 24 which are engaged by 25 a reentrant flange 24 on the base shell 14 to firmly secure the glass button and shell together and to lock the same against relative rotational displacement, as disclosed in the aforesaid co-pending application.

To insure the complete filling of the recess 21 by the solder 16, the said recess is made substantially semi-globular in shape and of such size as to conform as closely as possible to the natural shape of that portion of the drop of solder which is to be inserted therein. With such a shaped recess there are no sharp corners which might remain unfilled by reason of the sudden cooling of the solder forming the end contact. Consequently, there are no unfilled spaces into which the 30 solder might be forced to flow by the pressure exerted thereon during repeated insertion of the lamp in its socket, and therefore the initially assembled height of the solder above the base shell 14 and the glass button 15 is maintained at all 35

times during the life of the lamp. This is a very important feature inasmuch as a slight flattening of such a solder end contact might prevent its subsequent engagement with the corresponding contact of the lamp socket, thereby preventing completion of the circuit through the lamp filament and so foreshortening the useful life of the lamp.

As shown in Fig. 2, the solder 16, when inserted 10 into the recess 21, flows down into the opening 20 so as to partially fill the space between the wire 19 therein and the walls of the said opening. The wire 19 being tinned, the solder readily adheres thereto and so becomes firmly bonded to the 15 said wire. Because of this firm bond, and further because of the minuteness of the space (approximately 0.010 of an inch) between the wire 19 and the walls of the opening 20, no movement of the solder down through the opening 20 occurs when 20 pressure is applied to the outer surface of the globule of solder 16, so that the originally assembled height of the solder 16 above the base shell 14 and the glass insulation 15 is therefore maintained.

25 As will be noted particularly in Figs. 3 and 4, the recess 21 is provided with a small annular ridge 25 around the edge of the opening 20. This annular ridge is formed during the prefabrication of the glass insulator button 15, by the 30 plunger which forms the hole 20, and is a result of the carrying of a portion of the molten glass by the plunger down into the recess provided in the preforming mold for accommodation of the said plunger, said recess being slightly larger in 35 diameter than the plunger. As a consequence of this particular method of formation of the ridge 25, the upper surface 26 thereof is very ragged or irregular, as shown in Fig. 4. This irregular surface 26 therefore serves to prevent undesired 40 rotation of the solder 16 within the recess 21 when the lamp is screwed into a socket.

While the recess 21 and the drop of solder 16 forming the lamp end contact are shown applied to a preformed insulator button 15, it is obvious 45 that the same may be applied equally well to bases as made by the present method which consists in forming the glass insulation on the base shell while in a molten state.

What we claim as new and desire to secure by 50 Letters Patent of the United States is:

1. An electrical device comprising a bulb having an electric energy translation element sealed therein and a base mounted thereon, said base comprising a metal shell, an insulating member secured to an end of said shell and provided with a concave substantially semi-globular recess in its outer surface, and an end contact mounted on said insulating member, said shell and end contact being connected to opposite ends of said 55 electric energy translation element, said end contact consisting of a mass of readily fusible conductive material disposed within the said recess in direct contact with said insulating member and entirely filling the said recess.
- 60 2. An electrical device comprising a bulb having an electric energy translation element sealed therein and a base mounted thereon, said base comprising a metal shell, an insulating member secured to said shell and provided with a sub-

stantially semi-globular recess in its outer surface and an annular ridge having an irregular surface within said recess, and an end contact mounted on said insulating member, said shell and end contact being connected to opposite ends of said electric energy translation element, said end contact consisting of a mass of fusible conductive material disposed within the said recess and entirely filling the same, the irregular surface of said ridge being in interlocking engagement with said end contact to prevent rotation of said end contact within said recess.

3. A base for electric lamps or similar devices comprising a metallic shell and an insulating member secured to an end thereof, the outer surface of said insulating member being provided with a centrally located concave and substantially semi-globular recess for direct reception of a quantity of readily fusible conductive material.

4. The method of basing an electrical device comprising a glass bulb having a pair of lead-in wires extending from an end thereof, which method comprises forming a button of insulating material with engagement means at its periphery and a sub-globular recess in its upper surface, uniting said button at its rim to the upper end of a metallic base shell so as to form an interlocking engagement between the end of said shell and the said engagement means on said button to secure them against relative axial and rotative movement, uniting the said base shell at its lower end to the end of said bulb, connecting one of said lead-in wires electrically to said base shell, extending the other lead-in wire to the said recess in said insulating button, and forming an end contact by placing a drop of readily fusible conductive material in said recess directly in contact with the material of which said button is composed and also in contact with said last-named lead-in wire.

5. A base for electric lamps or similar devices comprising a metal shell and an insulating button member secured to an end thereof, the outer surface of said insulating member being provided with a substantially semi-globular recess for direct reception of a readily fusible metal contact, said recess having therein an annular ridge with projections thereon serving to lock a contact filling said recess against rotation within said recess.

6. An electrical device comprising a bulb having an electric energy translation element sealed therein and a base mounted thereon, said base comprising a metal shell, an insulating member secured to an end of said shell and provided with a substantially semi-globular recess in its outer surface, said recess having projections protruding from its surface, and an end contact on said insulating member, said shell and end contact being connected to said electric energy translation element, said end contact consisting of a mass of fusible conductive material disposed within the said recess and entirely filling it, said projections being in interlocking engagement with said end contact to prevent rotation of said end contact within said recess.
